INTERNAL COMBUSTION ENGINE

Jesse G. Vincent, Detroit, Mich., assignor to
 Packard Motor Car Company, Detroit, Mich., a
 corporation of Michigan

Application December 23, 1931, Serial No. 582,810

5 Claims. (Cl. 121—194)

This invention relates to internal combustion engines and particularly to the structure of the engine parts.

The construction of this invention is especially useful in Diesel engines where the explosions are particularly heavy and the engine must necessarily be sturdily made and well supported in order that vibration and noise may be minimized.

10 One of the objects of the present invention is to so make the various parts thereof that they will, when put together, form a rigid box-like structure capable of resisting vibration and of being supported rigidly on suitable mountings.

15 Another object of the invention is to so form the box-like parts of the engine that they may be readily machined and easily put together.

Another object of the invention is to form the various parts of the engine so that when they 20 are assembled the engine as a whole will present a relatively smooth outward appearance and will have practically all of the operating parts housed within itself.

Other objects of the invention will appear 25 from the following description taken in connection with the drawings, which form a part of this specification, and in which:

Fig. 1 is a vertical end view of an engine made in accordance with this invention;

30 Fig. 2 is an end view of the engine shown in Fig. 1 with the parts disassembled from each other but arranged in close relation to each other to indicate how they are joined together, and

Fig. 3 is a side view of the engine shown in 35 Fig. 1.

The engine shown in the drawings is preferably a Diesel engine of the marine type and it is adapted to be supported upon separated side beams such as those indicated at 10 in Fig. 1.

40 The crank case of the engine is composed of two principal parts, a lower section 11 and an upper section 12, each of these sections being of box-like construction in cross section as is shown by the end views, Figs. 1 and 2. The lower section 11 forms the sump or oil containing compartment and the upper section 12 forms a support for the various operating shafts of the engine. At the right, in Fig. 1, is shown a bearing 13 for a cam shaft to operate the fuel injection device, and at the left is shown a bearing 14 for a cam shaft for operating the engine valves. Between the crank case sections is formed a bearing 15 suitable for the engine crank shaft.

The lower crank case section 11, as shown in 55 Fig. 3, extends beyond the end of the upper sec-

tion to form the lower part of a gear box or transmission case, this extended part being indicated at 11a, and a separate detachable casting 12a is secured over the part 11a and to the end of the section 12 to complete the housing of the transmission. A cover 12b is provided for the top of the part 12a.

The lower crank case section 11 has a heavy flange 16 extending outwardly from each side and preferably running the full length of the 10 crank case including the extended part 11a, and the upper section 12 has a similar flange 17 on each side. These flanges are the main supporting legs of the engine and they are bolted together and to the supports 10 as by bolts 18, thus 15 rigidly connecting both sections of the crank case to the supports.

The upper crank case section 12 has its open sides closed by detachable covers 19 and 20, thus 20 completing the enclosure of the shafts within the casing.

Mounted upon the crank case is a cylinder block 21 secured to the crank case by suitable bolts, two of which are shown at 22 in Fig. 1. The casting for this cylinder block is also of somewhat 25 box-like section, its walls being extended to enclose some of the valve and injection mechanism. The sides of the cylinder block are closed by suitable detachable covers 23 and 24. The cylinder block 21 has its cylinders extending below the 30 lower face of the block and when the block rests in position on the crank case these extensions of the cylinders are within the upper part of the crank case. This construction is shown in the exploded view, Fig. 2, and the lower extension of 35 one of the cylinders is shown through an opening in the end of the crank case in Fig. 1.

Detachably mounted upon the upper end of the cylinder block is a casting 25 forming a head 40 for each of the cylinders. This cylinder head casting has secured to it on the right hand side an intake manifold 26 and on the left hand side an exhaust manifold 27.

Mounted above the cylinder head and detachably secured thereto and to the manifolds is a 45 cover 28 which covers the valve operating mechanism not shown in the drawing.

At each side of the cylinder block there are formed compartments 30 and 31, such compartments extending substantially the full length of 50 the cylinder block. The sides and top of the cylinder block adjacent the compartments are open, the manifold 26 resting on top of the cylinder block extending substantially across the open top of the compartment 30 and the head block 25 55

and the manifold 27 extending over the compartment 31. Depending from the manifold 26 is a flange 32 arranged to project into the compartment with its outer surface flush with the outer 5 face of the adjacent side wall of the cylinder block. A flange 33 depends from the manifold 27 and projects into the compartment 31, the outer face of this flange being arranged to lie flush with the outer surface of the adjacent side wall of the 10 cylinder block. The cover plate 23 is secured across its top to the flange 32 and the cover plate 24 is secured across its top to the flange 31, thereby providing a good seal at the top of the compartments. Because these flanges 31 and 32 are 15 removable from the cylinder block, machining of the walls forming the compartment can be readily accomplished because there is no interference such as would be caused if the flanges 31 and 32 were formed as a part of the upper side walls of 20 the cylinder block. Due to the similarity of the sides of the upper half of the crank case, the cylinder block and the manifolds, finishing of the surfaces along the sides thereof prior to assembly can be readily accomplished due to accessibility. 25 The same fixtures can be used for the finishing of both sides of the upper half of the crank case, the same fixtures can be used for finishing both sides of the cylinder block and the same fixtures can be used for finishing the adjacent portions 30 of the manifolds and the head. In addition to the symmetrical structure which is formed, the cost of finishing, from the standpoint of labor and fixtures, is low.

Thus is built up a very sturdy engine construction in which all the box-like structural parts are closely held together and formed into a rigid whole that is capable of withstanding the heavy explosions that are inherent in an internal combustion engine of the Diesel type.

40 While I have herein described in some detail a specific embodiment of my invention, which I deem to be new and advantageous and may specifically claim, I do not desire it to be understood that my invention is limited to the exact details of 45 the construction, as it will be apparent that changes may be made therein without departing from the spirit or scope of my invention.

Having thus described my invention, what I 50 claim and desire to secure by Letters Patent is: 1. In an internal combustion engine, the combination of upper and lower crank case sections, said sections being of box formation in cross section with the sides extending substantially in line vertically, said upper box section having open 55 sides, supporting flanges extending outwardly from the adjacent side walls of the sections, cover plates secured against the sides of the upper section over the openings therein, and means securing said supporting flanges together and to a support.

2. In an internal combustion engine, the com-

bination with upper and lower crank case sections having means formed therewith to support a crank shaft between them, the upper of said sections having means for supporting operating shafts therein, a cylinder block mounted upon 5 the crank case and having cylinder portions extending into the crank case, a detachable head mounted on the cylinder block, said head having each side wall extending substantially in a straight line both vertically and longitudinally 10 and formed with openings therein, separate intake and exhaust manifolds having portions engaging against the side walls of the head and secured in communication with the openings therein, and a cover extending over the cylinder 15 head and the manifold portions, said cover being secured against the top of the side walls of said manifolds.

3. In an internal combustion engine, a crank case having open side walls extending substantially in straight parallel lines, a cylinder block mounted upon the crank case and having its side walls open and in line with the side walls of the crank case, a detachable head formed with open side walls and mounted on the cylinder block, said head being of less width than the cylinder block and arranged short of the sides thereof with the sides extending in a straight line vertically and longitudinally, a cover mounted on the cylinder head having its side walls substantially in alignment with the side walls of the cylinder block, an intake manifold secured to the head and having a portion filling the space intermediate the cylinder block and the cover on one side of the engine, and an exhaust manifold secured to the head 35 and having a portion filling the space between the cylinder block and the cover on the other side of the engine.

4. In an internal combustion engine, the combination of a cylinder block having compartments 40 at the sides thereof, the top and side walls of the block being open to the compartments, a head structure over the top of the cylinder block, said head structure having depending flanges extending into the compartments in flush relation with the outer surface of the side walls of the block, and side cover plates for the compartments overlying the flanges and secured thereto.

5. In an internal combustion engine, the combination of a cylinder block having chambers at 50 the sides thereof, the top and side walls of the block being open to the chambers, an exhaust manifold overlying the open end of one of the chambers, an intake manifold overlying the open end of the other chamber, each manifold having a flanged portion extending into the adjacent chamber with the outer face flush with the outer surface of the adjacent side of the cylinder block, and side cover plates for the chambers overlying the flanges and secured thereto.

JESSE G. VINCENT.
